POSITIVE PRESSURE RESUSCITATOR

Henry Seeler, Dayton, Ohio, assignor to the
United States of America as represented by the
Secretary of the Air Force

Application January 28, 1952, Serial No. 268,653

5 Claims. (Cl. 128—29)

(Granted under Title 35, U. S. Code (1952),
sec. 266)

1

The invention described herein may be manufactured and used by or for the United States Government for governmental purposes without payment to me of any royalty thereon.

The present invention relates to a positive pressure resuscitator.

The primary object of the invention is to provide a resuscitator including a housing having a gas inlet tube extending therein equipped with a first valve movable from open to closed position and vice versa under the action of a pressure responsive diaphragm in the housing, wherein an exhaust tube extending into the housing has a second valve therein movable from closed to open position as the first valve is moved from open to closed position, wherein an outlet connection on the housing leads to a face mask and wherein an adjustably mounted spring means in the housing offers resistance to movement of the diaphragm as the diaphragm is moved by positive pressure developing in the housing during the inhalation phase of the resuscitation cycle occurring at the same time the first movable valve is open and the second movable valve is closed.

Another object of the invention is to provide a resuscitator including a housing having a gas inlet tube extending therein equipped with a first valve movable from open to closed position and vice versa under action of a pressure responsive means in the housing, wherein an outlet tube extends from the housing and is adapted to be connected to a face mask, wherein an exhaust tube extending into the housing has a second valve therein movable from closed to open position as the first valve is moved from open to closed position by means of a valve actuating linkage within the housing, and wherein the exhaust tube and outlet tube are coaxial with the inner end of the exhaust tube including an extension traversing the interior of the housing and extending outwardly through the outlet tube and of such a diameter as to provide an annular passage for gas flowing to the face mask. The above and other objects of the invention will become apparent upon reading the following detailed description in conjunction with the accompanying drawing, in which:

Fig. 1 is a central cross sectional view of the resuscitator taken longitudinally with respect to the inlet and outlet connections.

Fig. 2 is a side elevation view of the resuscitator and showing the central gas chamber in cross section.

Fig. 3 is a top plan view of the resuscitator and includes in this view a circular screen over the exhaust conduit which is optional.

2

Fig. 4 is a longitudinal cross section taken through the gas flow control tube leading into the resuscitator.

Referring to Figs. 1 to 4 of the drawing the resuscitator will be described in detail. The main body 1 is of generally cylindrical shape at one side which is closed by an exteriorly threaded cap or cover plate 2 having small openings 3 therethrough and which cap threads into the body or housing 1, as shown in Fig. 2. An annular shoulder within the body provides a seat for a circular diaphragm 4 having its marginal edges seated between similar circular gaskets 5. The flexible diaphragm 4 is adapted to actuate a slideable valve actuating rod or stem 6 secured to the diaphragm centrally thereof with similar disks 7 on the stem in clamping relation with respect to the diaphragm. The left-hand end of the stem 6 is provided with a circular enlargement 6' slidably situated in a hollow stud or button 8 threaded into the end wall of the body 1 and provided with a sealing washer or gasket 9 to prevent gas leakage. At the right-hand end of stem 6 there is a hollow guide post 10 integrally connected to a cup 11 interiorly of the cup and serving to slidably guide the stem. A light compression spring 12 situated around the post 10 provides resistance to movement of the stem and diaphragm assembly after movement to the right has proceeded far enough to cause contact with the spring. An additional spring 13 imposing very light pressure on the right-hand side of the diaphragm may be used to augment the effect of compression spring 12. The cup 11 is free for endwise sliding movement in a hollow boss 14 formed centrally of the end cap or cover 2. Means to adjust the position of the cup 11 is in the form of a large knob 15 including a pointer element 16 and a threaded post 17 centrally thereof. The post 17 is threaded into the boss 14 and serves to adjust the relative position of the cup 11 in the direction of the stem 6. Suitable indicia adjacent to knob 15 on the body 1 may be calibrated to indicate the maximum positive pressure developed during the inhalation phase of the resuscitation cycle.

Considering Fig. 1 it will be seen that a gas inlet fitting 20 extending from the body 1 has a knurled sleeve or collar 21 rotatably mounted thereon and retained in place by a small screw 22 extending in radial relation and having its inner end riding in an annular guide recess 23. A supplementary sleeve 24 inside collar 21 turns with the collar and has opposite cam slots to actuate the opposite end portions of a cross-pin 25 extending through axial slots 26 in the fitting

20. The pin 25 carries a stud 27 fixed to one end of a small aneroid bellows 28. The other or inner end of the bellows carries a hollow valve element 29 cooperating with a valve seat portion 30 at one end of a gas flow control tube 31. The tube 31 is retained in position as shown by a threaded washer 32. The valve element 29 has a central passage therein connected to the interior of fitting 20 by transverse passage so that even if the valve seats firmly on the valve seat 30 there will still be provision for a minimum gas flow into the resuscitator. A butterfly valve 33 in the gas flow control tube 31 near its outlet end is adapted to open and close to determine the duration and frequency of the inhalation and exhalation phases of the resuscitation cycle. The rotatable valve 33 is rigidly connected to a crank-shaft 34 to which is connected a small tension spring 35 adapted to snap the valve 33 open and closed as the stem 6 moves back and forth. As shown in Figs. 1 and 2 the upper end of the spring 35 is hooked through a small aperture in an intermediate flattened portion of the stem 6. As the longitudinally movable stem is reciprocated back and forth by action of the diaphragm 4 the line of action of the coil spring 35 is moved from one side to the other of the axis of rotation of the crankshaft 34. Thereby the butterfly valve 33 is snapped from open to closed position and vice versa.

Extending from the housing 1 and offset from the control or inlet tube 31 is a gas outlet connection 36 for a flexible conduit extending to a face mask. A gas outlet or exhaust tube 37 is screw threaded into a wall of the housing 1, as at 38, and has its free end extending through the interior of the housing and through the connection 36 in spaced coaxial relation. The annular passage 39 between the tubes 36 and 37 provides sufficient cross sectional area to carry the fresh supply of gas out of the housing 1 to the face mask. Since the products of respiration carry considerable moisture, the flow thereof out through the tube 37 prevents influx of water vapor into the housing 1 where moisture may freeze on the valve operating mechanism. A second butterfly valve 40 is rotatably mounted within the exhaust tube 37 and includes a central shaft element carrying a forked lever 41 for fitting around the free end of the crankshaft 34 in embracing relation. As the first butterfly valve 33 moves from open to closed position the second butterfly valve 40 moves from closed to open position respectively. It is noted also that the exhaust tube 37 is installed by insertion through the outer end of the outlet tube 36 and then threaded into place as shown by application of a spanner wrench in slots 42 provided in the outlet end of tube 37. The extension of the exhaust tube 37 to a point remote from the interior of the housing 1 is a feature of importance, since as noted above the moisture from the patient's lungs will be channelled out to the atmosphere through the tube 37 and very little can thus reach the housing proper. To prevent the ingress of small foreign objects the outlet end of tube 37 may be covered by a small circular screen 43 (Fig. 3) but this feature is optional. The principal objection thereto is based on the fact that in cold weather moisture may freeze on the screen and block the small passages therethrough.

In operation of the present resuscitator a source of oxygen or air at low pressure will be connected to the inlet fitting 20. The manual

adjustment of the valve element 29 will be made according to the vital lung capacity of the patient, this being a function of the relative size and body build of the patient. The aneroid bellows 28 will stay in a collapsed condition at altitudes near sea level but as the altitude increases the bellows will tend to expand and thus decrease the flow of gas into the inlet tube 31. The reason for providing the flow limiting action is that as the altitude increases the incoming gas has greater expansive force due to the lower barometric pressure. While the gage pressure of the gas supply connected to the inlet fitting 20 is more or less constant, its value is low in relation to sea level barometric pressure. Therefore the absolute pressure at the valve 29 will be reduced appreciably as the altitude increases and consequently the aneroid bellows 28 will tend to expand and throttle the gas flow into the gas inlet tube 31 from the inlet fitting 20. This regulation of the rate of flow with changes in altitude is especially desirable in aircraft use of the resuscitator and is accomplished without attention by the doctor or aid man. Resuscitation during flight may be necessary not only in everyday high altitude flight but also in air evacuation of sick and wounded patients.

Air or oxygen flows into the housing 1 when the butterfly valve 33 is open and this gas flows out through the annular passage 39 to the conduit leading to the face mask. As the patient's lungs fill up with gas the pressure in the housing increases to cause movement of the diaphragm 4 and valve actuating stem 6 to the right (Fig. 2). This movement is resisted by the adjustably positioned spring 12 and therefore the relative adjustment of the spring will determine how high the positive pressure will rise during the inhalation phase of the resuscitation cycle. When the stem 6 has moved far enough to the right to carry the spring 35 across the center of rotation of the crankshaft 34, the valve 33 will be snapped to closed position and at the same time the exhaust valve 40 will be snapped to open position. The products of respiration will now flow out through the exhaust tube 37 under the natural tendency for the chest and lungs to contract after being filled with gas. Thus the exhalation phase of the resuscitation cycle is accomplished at atmospheric pressure and for most purposes negative pressures are not necessary to good resuscitation action. As the lungs empty and the chest contracts to normal size, the pressure in the housing 1 is reduced to atmospheric pressure and the diaphragm moves back to the left under action of the light compression spring 13. The corresponding movement of the stem 6 and spring 35 causes the valve 33 to snap to open position again and the valve 40 to snap to closed position, thus starting the breathing cycle over again with the inhalation action accomplished under positive pressure.

In order to illustrate in more concrete manner the action of the altitude control means including aneroid bellows 28, an example of the possible pressures involved might be stated. The ground level barometric pressure will be about 760 millimeters of mercury and the additional pressure imposed by the resuscitation medium flowing in the fitting 20 may be about 20 millimeters of mercury. At sea level the absolute pressure on the bellows will therefore be near 780 millimeters. Now if the device is operating at 40,000 feet above sea level the barometric pressure will be only 190 millimeters of mercury while the resuscitation

pressure will still be near 20 millimeters of mercury. The absolute pressure on the bellows will now be in the region of 210 millimeters of mercury. Thus the difference between 780 and 210 represents the reduction in pressure on the bellows, whereby the expansion thereof will occur in going from sea level to 40,000 feet above sea level. It will be understood that aneroid bellows of the type under consideration will always contain an expansion spring means to cause the bellows to elongate as the external pressure thereon is reduced. Such a spring also overcomes the natural stiffness of the sheet metal walls of the bellows. Altitude responsive aneroid bellows are standard items and the interior construction thereof is not part of the present invention.

The present invention possesses features in common with my prior application Serial No. 212,818, now matured into Patent No. 2,581,450 of January 8, 1952.

The embodiment of the invention herein shown and described is to be regarded as illustrative only and it is to be understood that the invention is susceptible of variations, modifications and changes within the scope of the appended claims.

I claim:

1. A resuscitator comprising, a housing defining a gas receiving chamber, means providing a gas inlet into said housing including a tubular member, a first movably mounted valve in said tubular member, means providing a gas outlet from said housing for connection to a face mask, a gas exhaust tube extending through said housing and open to the atmosphere, a second movably mounted valve in said exhaust tube, a flexible diaphragm in said housing forming one wall of said chamber, a valve operating mechanism in said housing including a slidably mounted stem fixed to said diaphragm responsive to changes in pressure in said chamber during inhalation and exhalation phases of the resuscitation cycle, means interconnecting said stem and said valves to actuate said first valve from open to closed position and vice versa at the same time said second valve is operated from closed to open position and vice versa by action of rising and falling pressure in said gas receiving chamber, and an adjustable biasing means at one end of said stem acting in opposition to the rising pressure in said chamber during the inhalation phase of the resuscitation cycle.

2. A resuscitator comprising, a housing defining a gas receiving chamber, means providing a gas inlet into said housing, a first movably mounted valve in said gas inlet, tubular means providing a gas outlet from said housing for connection to a face mask, a gas exhaust tube open to the atmosphere extending through said housing and having a portion extending centrally through said tubular means in spaced coaxial relation, a second movably mounted valve in said exhaust tube, and a valve operating mechanism in said housing responsive to changes in pressure therein during inhalation and exhalation phases of the resuscitation cycle to actuate said first valve from open to closed position and vice versa at the same time said second valve is operated from closed to open position and vice versa by action of rising and falling pressure in said gas receiving chamber.

3. A resuscitator comprising, a housing defining a gas receiving chamber, means providing a gas

inlet into said housing, a first movably mounted valve in said gas inlet, tubular means extending outwardly from a wall of said housing for connection to a face mask, a gas exhaust tube extending across the interior of said housing having one open end fixed in a wall of said housing with the other open end extending through said tubular means in spaced coaxial relation, a second movably mounted valve in said exhaust tube, and a valve operating mechanism in said housing connected to said valves and responsive to changes in pressure therein during inhalation and exhalation phases of the resuscitation cycle to actuate said first valve from open to closed position and vice versa at the same time said second valve is operated from closed to open position and vice versa by action of rising and falling pressure in said gas receiving chamber.

4. A resuscitator comprising, a housing defining a gas receiving chamber, a gas inlet tube fixed to a wall of said housing and extending into said chamber, a first butterfly valve rotatably mounted in said gas inlet tube, means providing a tubular gas outlet on said housing and extending thereto from generally parallel to said gas inlet tube, a gas exhaust tube extending through said housing and through said tubular gas outlet in spaced coaxial relation thereto, a second butterfly valve rotatably mounted in said gas exhaust tube, a flexible diaphragm in said housing and forming one wall of said gas receiving chamber, a slidably mounted valve actuating stem fixed to said diaphragm centrally thereof, a crankshaft fixed to said first butterfly valve and having a crank arm portion extending at a right angle to said stem and spaced therefrom, an overcenter coil spring extending from said crankarm to said stem to cause said first valve to move from open to closed position and vice versa as said diaphragm is moved back and forth by rising and falling pressure in said gas receiving chamber, and means connected between said second butterfly valve and said crankarm to cause said second valve to simultaneously move from closed to open position as said first valve is moved from open to closed position.

5. A resuscitator comprising a housing providing a gas receiving chamber, a gas inlet tube connected thereto and extending within said housing, a butterfly valve mounted in said tube, a tubular gas outlet extending from said housing, a gas exhaust tube mounted in said housing and extending therethrough concentric with said gas outlet, a second butterfly valve in said gas exhaust tube, a diaphragm, responsive to changes in pressure, forming one wall of the gas receiving chamber, a control stem mounted centrally of said diaphragm extending therefrom, crankshaft means directly interconnecting said butterfly valves, and means connected to said stem and said valve interconnecting means whereby upon a predetermined pressure in said gas receiving chamber, the control stem is operative to close the inlet valve and open the exhaust valve.
